US00D619625S

(12) **United States Design Patent**
Schroeder et al.

(10) **Patent No.:** US D619,625 S
(45) **Date of Patent:** ** Jul. 13, 2010

(54) **THERMAL LINE STRIPER**

(75) Inventors: **James C. Schroeder**, Ramsey, MN (US); **Roland M. Bedard**, Forest Lake, MN (US); **Steven H. Fredrickson**, Minneapolis, MN (US); **Thomas L. Triplett**, Rockford, MN (US)

(73) Assignee: **Graco Minnesota Inc.**, Minneapolis, MN (US)

(**) Term: **14 Years**

(21) Appl. No.: **29/340,826**

(22) Filed: **Jul. 27, 2009**

(51) **LOC (9) Cl.** **15-03**

(52) **U.S. Cl.** **D15/13; D15/10**

(58) **Field of Classification Search** **D15/10-13; D23/213, 225; 118/305; 427/137; 239/150, 239/146, 147, 172, 155, 159, 164, 165, 176, 239/683-687, 754; 404/93, 94**

See application file for complete search history.
